SLIP

Mary C. Hennessy, New York, N. Y., assignor to
 Franklin Simon & Co., Inc., New York, N. Y.,
 a corporation of New York

Application November 18, 1935, Serial No. 50,455

4 Claims. (Cl. 2—73)

This invention relates to wearing apparel, and has for an object to provide an improved article of wearing apparel in the nature of a slip and to provide a construction which may be made in quantities but which will readily accommodate itself to slightly different sizes of persons.

Another object of the invention is to provide an improved slip which will automatically accommodate itself to persons shaped slightly differently though technically of the same size.

A further object, more specifically, is to provide a slip having a specially constructed bodice with certain parts elastic and certain parts inelastic, the same being associated with a skirt section of elastic panels arranged in a way to readily adjust itself to the waistline and to the hips of the person wearing the garment.

In the accompanying drawing:

Fig. 1 is a perspective view of a slip disclosing an embodiment of the invention, the same being shown applied to a figure;

Fig. 2 is a front view of the slip shown in Fig. 1;

Fig. 3 is a rear view of the slip shown in Fig. 1;

Fig. 4 is a view showing a group of members or sections forming the front part of the bodice illustrated in Fig. 1;

Fig. 5 is a view similar to Fig. 4 but showing the rear part of the bodice;

Fig. 6 is an elevation of the front and rear panels of the slip shown in Fig. 1; and

Fig. 7 is an elevation of the side panels of the slip shown in Fig. 1.

Referring to the accompanying drawing by numerals, 1 indicates the bodice as a whole and 2 the skirt as a whole. Suitable suspenders or supporting straps 3 and 4 are connected to the bodice to act as supports for the garment. In the making of a slip by a tailor the parts are cut to fit in a general way at first, and after the same has been placed on the person the various parts are trimmed away to the proper size and proper fit. In producing slips in quantities to be sold over the counter this is not possible. In the present invention a construction has been provided which is aimed to secure substantially the same results as the tailor fitted slip while permitting quantity production.

In carrying out this general idea the respective panels 5, 6, 7, and 8 are formed of elastic material, elastic and stretchable in one direction. The panels 7 and 8 are of the same size and shape while the front panel 5 is as long as the back panel 6 but is of less width. All of the

panels 5 to 8 inclusive are positioned in the completed garment so that they will stretch circumferentially, the warp thread of the respective panels being at about a forty-five degree angle to the horizontal, while the weft threads 5 are naturally at right angles to the warp threads. When the various panels just described are connected by suitable stitching 9, the upper ends which are round form in a certain sense scallops. The waistline, for instance, is approximately at 10 a point half way the height of the curved upper end of the front panel 5. All of the panels at their upper ends are connected to the bodice 1 which is formed from six pieces of material as shown in Figs. 4 and 5, instead of being formed 15 of one or two pieces. The pieces, as mentioned, are necessary to secure the desired fit and adaptation of the bodice to persons of slightly different sizes and shapes.

The bodice is formed at the front with a panel 10 which is connected by a line of stitching to panel 11, which in turn is connected by a line of stitching to panel 12. At the rear the panel 13 is connected by a line of stitching to panel 14, which in turn is connected by a line of stitching to panel 15. The respective front and rear panels are connected together by suitable lines of stitching 16 and 17 slightly back of a central line under the arms. This is illustrated particularly in Fig. 3 and is caused by the fact 20 that the panels 10 to 12 are longer than panels 13 to 15. This arrangement of the panels produces the desired fit with greater fullness at the front than at the back. The panels 11 and 14 are formed of inelastic material and are not 25 stretchable in any direction, while the remaining panels at the front and rear are stretchable circumferentially in a similar manner to the skirt section 2. The panel 11 is intended to fit across the center at the breast when the garment is in 30 use and the natural downward pull caused by the fit of the garment will cause the panels 10 and 12 at the front to conform to the shape of the body above and below the breast while similar results are secured at the back, that is, the 35 elastic sections will cause the garment to conform itself to the shape of the back. By reason of these arrangements of parts and the positioning thereof so as to stretch in certain directions results in the garment conforming or moving 40 itself to the shape of a person.

It has been found that persons who are technically of the same size as far as garments are concerned are shaped slightly different, namely, sometimes a person has larger hips than others 45

- and at other times the breasts are larger. In order to take care of these varying conditions the inelastic sections 10 and 14 have been provided and positioned as shown in the drawing, with 5 the remaining part of the bodice arranged to stretch and conform to the respective parts of the body above and below the inelastic panels. As the panels 10 and 13 are stretchable circumferentially they will coat with the panels 10 of the skirt section, whereby a proper fit at the waistline may be secured whether it is what is known as a high waist or a low waist.

I claim:

1. A slip of the character described formed 15 to extend from a point above the breasts of the wearer to a point below the knees comprising a skirt section and a bodice section, the skirt section extending from a point adjacent the knees of the wearer to the waistline, said section 20 being formed with front, rear and side panels of the same general shape, each of said panels being rounded at the top and tapered from top to bottom with a slightly outward flare, the side panels being of the same size while the front 25 panel is slightly narrower than the rear panel whereby greater fullness is provided to take care of the hips, lines of stitching for connecting said panels together so that the upper ends will present a scalloped formation, and a line of stitching 30 for connecting the upper end of the skirt section to the lower end of the bodice, said lower end of the bodice being provided with a scalloped concaved edge portion for fitting the upper end of the skirt section with the lower part 35 stretchable circumferentially to conform to the body while the central part is substantially non-stretchable to provide a support for the breasts of the wearer.
2. A slip of the character described comprising 40 a skirt section formed with a plurality of panels, all of said panels being of material stretchable in one direction, with the respective panels positioned to stretch circumferentially when made up into a slip, a bodice connected to 45 the upper end of said skirt section, said bodice

being formed with upper and lower panels adapted to entirely encircle the body of a person when the garment is in use, said upper and lower panels being circumferentially elastic and stretchable, and a central panel inelastic and non-stretchable at the front and back adapted to entirely encircle the body of the person using the garment, said last mentioned panel being positioned at the front to fit over the center of the breasts of the person wearing the garment 10 so as to act as a support for the breasts. 5

3. A slip comprising a skirt section and a bodice section, said sections adjacent their meeting edges forming the waistline of the garment, said bodice having front and rear central circumferentially extending panels of non-elastic material connected together end to end substantially at the sides of the garment and front and rear upper and lower circumferential bands of material elastic circumferentially connected to 20 together end to end substantially at the sides of the garment, said front and rear upper and lower panels being connected respectively to the upper and lower circumferential edges of said front and rear central panels. 25

4. A slip comprising a skirt section and a bodice, said skirt section being elastic and stretchable circumferentially, said bodice being formed with a lower section entirely encircling the body of the wearer, said lower section being 30 elastic and stretchable circumferentially to conform to the waistline and to also conform to the lower part of the breasts of the wearer, an intermediate section formed to entirely encircle the body of the person wearing the garment, 35 said intermediate section being inelastic in all directions and at the front substantially straddling the breasts of the wearer so as to act as a support therefor, and an upper section formed to entirely encircle the wearer, said upper section 40 being elastic and stretchable circumferentially and acting at the front to snugly fit the body at the upper part of the breasts of the wearer.
